Robert D. Parry, 7240 Algonquin Drive,
Cincinnati, Ohio 45243

Filed Mar. 22, 1968, Ser. No. 11,092

Term of patent 14 years

U.S. Cl. D88—5
Int. Cl. D24—01

FIGURE 1 is a side view of the hand grip as designed for use with a crutch showing my new design;

FIGURE 2 is an enlarged side view of the hand grip from that side shown in FIGURE 1;

FIGURE 3 is a side view of the hand grip of that side opposite to the side shown in FIGURE 2;

FIGURE 4 is a front-end view of the hand grip;

FIGURE 5 is a rear-end view of the hand grip; and

FIGURE 6 is a side view of a modified embodiment of the hand grip illustrated in FIGURE 1 as designed for use with a cane.

The broken lines depicted in the above described figures are shown for illustrative purposes only.

I claim:

The ornamental design for a hand grip for a crutch or cane, substantially as shown and described.
